(57) CLAIM

The ornamental design for a label, as shown and described.

DESCRIPTION

FIG. 1 is a top view of the label in an open position;

FIG. 2 is an enlarged top view of the label in a first closed/folded position; and,

FIG. 3 is a further enlarged top view of the label in a second closed/folded position.

In the drawings, the broken lines represent fold lines.

1 Claim, 3 Drawing Sheets

FIG. 1

FIG. 3
